CLAIM

The ornamental design for a stud for an article of footwear, as shown and described.

DESCRIPTION

FIG. 1 is a side elevational view of a stud for an article of footwear showing my new design;

FIG. 2 is a top plan view thereof;

FIG. 3 is a sectional view on the line 3—3 of FIG. 2; FIG. 4 is a fragmentary section on the line 4—4 of FIG. 2;

FIG. 5 is a fragmentary section on the line 5—5 of FIG. 2;

FIG. 6 is an inverted plan view of said stud, and FIG. 7 is a side elevational view thereof as seen at right angles to the view shown in FIG. 1.

FIG.1.

FIG.2.

FIG.3.

FIG.4.

FIG.5.

FIG. 6.

FIG. 7
